UNITED STATES PATENT OFFICE.

GEORGE WESTINGHOUSE, JR., OF PITTSBURG, PENNSYLVANIA.

TELEGRAPHIC RELAY.

SPECIFICATION forming part of Letters Patent No. 352,725, dated November 16, 1886.

Application filed August 30, 1886. Serial No. 212,178. (No model.)

To all whom it may concern:

Be it known that I, GEORGE WESTINGHOUSE, JR., residing at Pittsburg, in the county of Allegheny and State of Pennsylvania, a citizen of the United States, have invented or discovered certain new and useful Improvements in Telegraphic Relays, of which improvements the following is a specification.

In the accompanying drawings, which make part of this specification, Figure 1 is a vertical sectional view of my improved relay. Fig. 2 is a top plan view of the same, the cap or cover being removed. Fig. 3 is a sectional view of a detached portion of the make-and-break mechanism, illustrative of the operation of certain parts; and Fig. 4 is a top plan view of the parts shown in Fig. 3, the cap or cover being removed.

My invention relates to certain improvements in electrical relays; and, in general terms, it consists of certain combinations, with the magnet and armature, of a rod or stem operated by movements of the armature, and springs pressed into end contact by the rod, such springs operating both as a stop to limit movement of the armature and as a local-circuit make-and-break, as hereinafter more fully described and claimed.

In the drawings, A represents a base-plate, by preference of cast metal, having therein holes a, which receive tightly the ends of core-magnets B B, and thereby support, or assist in supporting, the magnets and their helices B' B', as well as the mechanism carried thereon. The position of the magnets and their helices is by preference vertical. The lower ends of the magnets protrude from the under face of the plate A, and, when magnetized, attract the end-pivoted armature b. This armature moves vertically, being raised by attraction of the magnets and lowered by gravity. It is guided in its movements by screw b', which also affords an adjustable stop to arrest back movement of the armature. A cap, D, incloses the operative parts beneath the bed-plate, such cap being attached by screws d, and is thereby readily removable. The armature is adjusted by its weight for a given battery power, though it may be used with good results with a variable battery, sufficient in strength at its minimum to raise the armature through the magnets.

Line or circuit connection is made with the helices B' by binding-posts D' D', electrical connection being made from the posts through the helices in the usual way.

A heel-bar, B², connects the two magnets at their upper end and upon this bar is secured a block, C, by screws c, such block carrying a head, C, of suitable electric insulating material, as hard rubber. A screw-cap, C², incloses the upper part of the head, within which is made a chambered recess, e, with a central hole, e', therein, which opens to a passage, e', made vertically through the block C, and continued therefrom through connecting-tube F and base A. The bottom of recess e is by preference beveled or countersunk at or around the central opening, and two or more metal springs, i, are fastened by screws i' at or near the rim of the recess, on opposite sides. The free ends of these springs incline or converge downward to the central opening, e', terminating in close proximity over or in such opening. In normal position the springs do not make electrical contact, and circuit connected to them, as at n, Fig. 2, will be open.

In order to make contact or close circuit, a rod, R, is passed from the armature on which it rests upward through tube F and block C', terminating in a flattened head, r, within the opening e'. Upward lift of the armature raises the rod, thereby pressing the head r upon the points of springs i and closing electrical connection between them by a sliding contact. Continuation of upward lift on the rod causes the ends of springs i to abut against each other, as in Fig. 3. A stop is thus effected, preventing further upward movement of the armature. This stop is so adjusted by the length and position of the springs as to prevent contact between the armature and the magnets.

It will be observed that the ends of springs i have an appreciable extent of sliding movement upon the head r, between first contact therewith and the step made by their abutting ends. This sliding contact is made in the most favorable manner for securing good electrical connection, both on account of its continuation and also on account of the scraping action of the spring-points upon the head, tending to preserve bright metallic contact-surfaces. Both springs bearing upon the head

may make electrical connection therethrough; also, electrical connection may be made between them directly when their ends are brought in contact, as in Fig. 3. The operation of the springs and rod in making this connection is similar to a toggle-joint, the ends of the spring being pressed together hard, thereby giving good electrical connection. A double opportunity is thus afforded for making circuit through the springs, and these, in addition to the advantages of sliding contact, afford practically complete assurance of making circuit-connection without risk of failure from defective metallic contacts.

If it is desirable to control more than one circuit by the relay, additional springs may be employed, substantially like the springs *i*, for example, as illustrated in Fig. 4, where two separate springs *i i*, electrically insulated from each other, are secured on one side, and a single spring on the other side. In this case the single spring forms a common return-connection for circuits connected to the other two. Provision may thus be made for making and breaking any desired number of circuits. Also, if desired, suitable electrical connection may be made by a circuit-line with rod *R*, such circuit being made or completed by contact of head *r* with one or more of the springs *i*, and such useful application of the rod for circuit-connection I consider as coming within my invention.

My improved relay is designed more particularly for use in signal-circuits for railway-service. It is an important consideration in such service that the relay should be simple in construction, certain in operation, and should not require attention for making adjustments, &c. These and similar requirements are fully met by the relay shown and described herein.

The certainty of gravity as a motive power for withdrawing the armature is employed, instead of the unreliable action of springs. Sliding contact is afforded for making circuit-connection, in addition to mere abutting contact, and this sliding contact is continued or in operation an appreciable time before the stop is reached. These and other features of construction, hereinbefore described, make this relay peculiarly adapted to the uses mentioned. I do not wish, however, to limit my invention to such uses, but include therein all to which a relay of this character may be applied.

I claim herein as my invention—

1. In a relay, the combination of a movable armature, a rod carried on and movable with the armature, and two or more electrically-insulated springs for making and breaking circuit located transversely to the line of movement of said rod, electric connection being made between the springs by direct end-pressure of the rod thereon, substantially as set forth.

2. Two or more electrically-insulated springs having their free ends adjacent and movable into and out of end-abutting contact, in combination with a magnet, an armature, and a rod carried on the armature and movable thereby against the ends of the springs to press them into contact, substantially as described, whereby electric circuit is made between the springs by sliding contact of their ends upon the rod, and movement of the armature toward the magnet is stopped by the abutting springs.

3. The recessed head *C*, in combination with downwardly-converging spring-electrodes *i i*, in any desired number, rod *R*, and electrically-controlled armature *b*, substantially as set forth.

4. Two or more converging springs, *i*, having their free ends normally open but movable into abutting contact by pressure thereon, in combination with rod *R*, end-pivoted armature *b*, and an electrically-excited magnet for moving the armature, such movement being stopped by abutting contact of the springs by pressure of the rod thereon, substantially as set forth.

5. The combination of an electrically-excited magnet, a vertically-movable armature lifted by magnetic attraction and withdrawn by gravity, a rod carried on and movable with the armature, and two or more electrically-insulated springs converging downward over the rod, such springs being normally open and movable under pressure of the rod thereon into an abutting contact, substantially as and for the purposes set forth.

In testimony whereof I have hereunto set my hand.

GEO. WESTINGHOUSE, JR.
